Attorney

UNITED STATES PATENT OFFICE

ALEXIS PRESTON STEELE, OF STATESVILLE, NORTH CAROLINA

BRICK AND TILE MACHINE

Application filed July 3, 1928. Serial No. 290,222.

This invention relates to a brick and tile machine and has relation more particularly to a device of this kind known as a straight line combined machine, and it is an object of the invention to provide a supporting means for the shaft comprised in the machine at a point between the pugging portion and the expressing portion of the shaft and contacting with a spiral carried by the shaft.

10 The invention also has for an object to provide an intermediate bearing means for the shaft of a straight line combined machine co-acting therewith in a manner whereby the shaft may be maintained in desired position 15 with the pug tub and barrel and which means offers no hindrance to the desired travel of the material, such as clay or shale, to the expressing end of the shaft.

20 A further object of the invention is to provide means for maintaining a long overhung shaft in or near the center of the pug tub and barrel so that the knives carried by the pug portion of the shaft and the spirals carried by the expressing portion of the shaft will not 25 touch or drag on the tub or barrel.

20 The invention consists in the details of construction and in the combination and arrangement of the several parts of my improved brick and tile machine whereby certain important advantages are attained and the device rendered simpler, less expensive and otherwise more convenient and advantageous for use, as will be hereinafter more fully set forth.

35 The novel features of my invention will hereinafter be definitely claimed.

In order that my invention may be the better understood, I will now proceed to describe the same with reference to the accompanying drawings, wherein:

Figure 1 is a view in top plan illustrating a brick and tile machine constructed in accordance with an embodiment of my invention;

40 Figure 2 is an enlarged fragmentary view partly in side elevation and partly in section illustrating the supporting means for the combined shaft at the outer portion thereof;

Figure 3 is a sectional view taken substantially on the line 3—3 of Figure 2;

50 Figure 4 is a detailed sectional view illus-

trating a further embodiment of the invention.

As disclosed in the accompanying drawings, 1 denotes the barrel of a straight line combined machine which is carried by an end 55 and constitutes a continuation of a pug tub 2. The outer end of the barrel 1 has secured thereto a casting 3 through which the material, such as clay or shale, is fed into the die 4 carried by the outer reduced end of the casting 3.

Disposed axially of the barrel 1 and substantially central through the tub 2 is a shaft 5, said shaft extending on through for power application and thrust load. As herein disclosed, the rear end portion of the shaft 5 is connected by a flexible coupling 6 with an overhanging shaft 7 adapted to be driven in any desired manner. The portion of the shaft 5 within the tub 2 has extending 65 outwardly therefrom the pugging knives 8 of a conventional type, while the portion of the shaft within the barrel 1, or what might be termed the expressing portion of the shaft, has mounted thereon for rotation therewith 70 a spiral 9. This spiral 9 together with the shaft 5 extends within the casting 3 and terminates closely adjacent to the outer end of the casting 3, and more particularly the die 4 carried thereby. The casting 3 can be considered as a part of the barrel 1.

The inner end of the spiral 9 is continued by an extension spiral 10 which is disposed along the portion of the shaft 5 between the pug portion and the expressing portion of the shaft and the periphery of said extension spiral 10 is provided with a relatively wide rim 11 to provide an increased bearing surface. The extension spiral 10 may also be termed a supporting spiral for reasons which will hereinafter be apparent, and in the present embodiment of my invention said extension or supporting spiral 10 is inserted in the forward end portion of the tub 2 or that portion of the tub 2 immediately adjacent to 85 the barrel 1.

The forward end portion of the tub 2 is provided in its lower wall with a series of elongated slots 14 spaced apart in a direction circumferentially of the shaft 5 and imme- 100

diately below the extension or supporting spiral 10.

Insertible from without through these slots 14 are the bearing blocks 15 preferably of wood although said blocks may be made of such other material as desired. The inserted edge of each of the blocks 15, as herein disclosed, is straight and provides a relatively broad supporting surface with which 10 the rim 11 of the extension or supporting spiral 10 directly contacts, thus assuring the shaft 5 being effectively maintained in desired working position with respect to the barrel 1 and the tub 2.

15 Engaged over the outer rear marginal portion of each of the blocks 15 is an elongated member 16 of metal or other desired material and which is provided in its inner face with a pocket 17 which snugly receives the outer 20 marginal portion of the block 15.

Extending outwardly from the wall of the tub 2 closely adjacent to the opposite ends of a slot 14 are the threaded shanks 18 which are freely disposed through the extremities 25 of the members 16. Threaded upon said shanks 18 and contacting with the outer face of the associated member 16 are the adjusting nuts 19. By requisite turning movement of these nuts 19 the adjacent member 16 and 30 associated block 15 will be forced inwardly of the tub 2 to compensate for such wear as may occur in connection with either the block 15 or the spiral 10 or both, thus assuring maintenance of the shaft 5 in desired working 35 position. The extension or supporting spiral 10 permits an unobstructed travel of the material, such as clay or shale, within the barrel 1 for expressing action by the spiral 9 and the portions of the blocks 15 disposed 40 within the tub 2 serve as additional ribs which, in connection with the ribs 20 disposed along the inner faces of the barrel 1 and casting 3, will hold the material under pressure against revolving or rotating with 45 the spiral.

It is to be noted that the bearing blocks 15 are set higher on one side than on the other and thus offsetting any tendency of the supplemental or supporting spiral 10 and the 50 adjacent portion of the shaft 5 to move laterally when the spiral 10 is in rotation. In practice, the spiral 10 rotates in the direction indicated by the arrow *a* with a natural 55 tendency to move the shaft laterally in the same general direction but, as before stated, this is prevented by providing the higher block 15. In fact, it is of advantage to have the uppermost block to the right of the spiral 10 positioned above the horizontal center of 60 such spiral.

In the embodiment of the invention as illustrated in Figure 4, the extension or supporting spiral 10 has contacting therewith the bearing rollers 21 to maintain the desired 65 positiohing of the shaft 5.

It is to be noted that the tub 2 has its open top face extending above the supporting spiral 10. This is of importance as such open space above the spiral 10 relieves said spiral against pressure therearound but allows the pressure from below to act upon the spiral 10 including its hub and upon the rim 11 of the spiral to help carry the load and thus relieve the load on the rim 11 and the bearing blocks 15.

From the foregoing description it is thought to be obvious that a brick and tile machine constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

90 I claim:

1. In combination with the shaft of a straight line combined brick and tile machine common to both the tub and barrel, a driving means, a flexible connection between said driving means and an end portion of the shaft, and supporting means engageable from below with the shaft between the pugging portion and the expressing portion of the shaft.

100 2. In combination with the shaft of a straight line combined brick and tile machine common to both the tub and barrel, a driving means, a flexible connection between said driving means and an end portion of the shaft, supporting means engageable from below with the shaft between the pugging portion and the expressing portion of the shaft, said means including a spiral carried by the shaft, and supporting members carried by the machine and with which the periphery of the spiral contacts.

110 3. In combination with the shaft of a straight line combined brick and tile machine common to both the tub and barrel, a driving means, a flexible connection between said driving means and an end portion of the shaft, supporting means engageable from below with the shaft between the pugging portion and the expressing portion of the shaft, said means including a spiral carried by the shaft, and supporting members carried by the machine and with which the periphery of the spiral contacts, the peripheral portion of the spiral being provided with a rim to afford increased contacting surface.

120 4. In a straight line combined brick and tile machine, the combination with the shaft common to the tub and barrel; of a supporting spiral carried by the shaft between the

5 pugging portion and the expressing portion, and supporting means for the shaft engageable with the periphery of the spiral, said supporting means coacting only with one side of the spiral above the horizontal center of the spiral.

10 5. In a straight line combined brick and tile machine, the combination with the shaft common to the tub and barrel; of a supporting spiral carried by the shaft between the pugging portion and the expressing portion, and supporting means for the shaft engageable with the periphery of the spiral from below and at one side at a point above the horizontal center of the spiral.

15 6. In a straight line combined brick and tile machine, the combination with the shaft common to the tub and barrel; of a supporting spiral carried by the shaft between the pugging portion and the expressing portion, and supporting means for the shaft engageable with the periphery of the spiral, said supporting means being higher at one side of the spiral than at the other.

20 25 7. A combined brick and tile machine comprising a tub and barrel, a shaft common to the tub and barrel, a supporting spiral carried by the shaft between the pugging portion and the expressing portion, and supporting means for the shaft engageable with the periphery of the spiral, the portion of the tub above the spiral being open.

25 8. In a straight line combined brick and tile machine, the combination with the shaft common to the tub and barrel; of a supporting spiral carried by the shaft between the pugging portion and the expressing portion, and supporting means for the shaft engageable with the periphery of the spiral, said supporting spiral being free of pressure from above.

30 40 45 9. In combination with the shaft of a straight line combined brick and tile machine common to both the tub and barrel, a driving means, a flexible connection between said driving means and an end portion of the shaft, and supporting means for the shaft positioned between the pugging portion and the expressing portion of the shaft.

50 55 50 In testimony whereof I hereunto affix my signature.

ALEXIS P. STEELE.
